B. C. BURKETT

LIGHTNING ROD CONNECTER

Filed June 4, 1924

UNITED STATES PATENT OFFICE.

BYRON C. BURKETT, OF FREMONT, OHIO, ASSIGNOR TO THE BURKETT LIGHTNING ROD COMPANY, OF FREMONT, OHIO, A CORPORATION.

LIGHTNING-ROD CONNECTER.

Application filed June 4, 1924. Serial No. 717,699.

The present invention relates to a lightning rod connector and has for its object to provide a device of this character which embodies novel features of construction, whereby the collector rod can be effectively connected to the conductor cable which extends across the structure and has one or both ends thereof grounded.

Further objects of the invention are to 10 provide a lightning rod connector which is comparatively simple and inexpensive in its construction, which can be easily and quickly applied to the conductor cable, which does not require any screws or other fastening 15 elements for its installation, and which provides an efficient electrical connection for conveying the electric current from the collector member to the conductor cable.

With the foregoing and other objects in 20 view the invention consists in certain combinations and arrangements of the parts as will more fully appear as the description proceeds, the novel features thereof being pointed out in the appended claims.

For a full understanding of the invention reference is to be had to the following description and accompanying drawings, in which,

Figure 1 is a perspective view showing 25 the manner of applying the invention to a building.

Figure 2 is a side elevation of the connector showing the manner of applying it to a conductor cable, the lightning rod being 35 broken away and shown in section.

Figure 3 is an end view thereof.

Figure 4 is a sectional view on the line 4-4 of Figure 2.

Figure 5 is a sectional view on the line 40 5-5 of Figure 2.

Figure 6 is a sectional view on the line 6-6 of Figure 2.

Figure 7 is a detail view of one of the 45 blanks from which the complementary sections of the connector are formed, and

Figure 8 is a detail view of one of the hinge members which are used for connecting the complementary sections.

Corresponding and like parts are referred 50 to in the following description and indicated on all of the views of the drawing by like reference characters.

The connector is employed for connecting the lightning rod or other collector element 55 to the conductor cable which is carried across

the building in suitable places and is grounded so that the electricity will be carried to the ground and injury to the building or other structure prevented. The connector has an inverted Y-shaped formation and 60 comprises a pair of similar and interchangeable complementary sections 1-1, which are adapted to be stamped and shaped from sheet metal. The blank A from which one of the sections is formed is shown by Figure 65 7 in the shape which it has when it is first stamped from a piece of flat sheet metal. After being stamped the blank A is shaped by bending the stem and arms thereof so that they have a concave formation and are 70 substantially semicircular in cross section. Each of the sections 1 includes a stem 1^a and a pair of diverging legs 1^b, the latter being shown as having a curved formation. Each of the diverging legs terminates in a 75 cable engaging foot 2, said foot members being arranged in alignment with each other and on an axis which is at an angle to the axis of the stem. The foot members 2 are bent transversely into substantially semi-cylindrical form so that they can be readily 80 fitted upon the conductor cable 3.

One of the legs 1^b of each of the complementary sections 1 is formed with an integral tongue 4, and in a similar way the outer end 85 of one of the foot members 2 of each of the sections is formed with an integral tongue 5. When two of the sections 1 are applied to each other with their concave faces in abutting relation, the tongues 4 can be bent 90 around the respective legs of the connector and the tongues 5 can be bent around the cable engaging sleeves formed by the foot members 2, there being one tongue 4 for each of the diverging legs and one tongue 5 for 95 each of the cable engaging sleeves.

The foot members 2 are shown as provided with openings 6 which are engaged by a link or hinge element 7. These connecting link members 7 originally have an inverted U-shaped formation, as shown by Figure 8, and after the arms thereof are passed through the openings 6 of the feet 2 they are bent toward each other in the manner indicated by Figure 5. The two complementary sections 1 are thus connected at their lower ends by a loose joint which acts in the manner of a hinge to admit of the sections being swung apart a sufficient amount 100 to fit the cable engaging sleeves upon the 105 110

cable. After this has been done the tongues 4 and 5 are wrapped around the diverging legs and cable receiving sleeves, respectively. The lighting rod or collector element 8 is of tubular formation or has a tubular base which can be fitted over the stem 1^a, thereby cooperating with the flexible tongues and hinge elements to hold the complementary sections 1 securely in position. No screws, bolts or other separate fastening elements are needed for this purpose, and the air terminals or collector members can be easily and quickly applied to the conductor cable without the use of any special tools or equipment.

The feet 2 are extended laterally beyond the diverging legs 1^b and provide elongated cable receiving sleeves which have an extended contact or engagement with the cable so that a splendid electrical connection is established therewith. The stem 1^a and diverging legs 1^b of each section are substantially semi-circular in cross section, so that when the two sections are assembled the different parts of the connector are tubular in formation, thereby imparting strength to the connector and giving it a uniform and symmetrical design. The connector has a two point attachment to the cable and the diverging legs at the base thereof avoid a sharp angular connection between the air terminal or collector member and the cable. It has been found that the electricity does not pass as readily through a sharp angular connection as around a curved or inclined connection and the diverging legs of the present device provide an easy path for the electricity to travel, so that the electricity will be carried to the ground with a minimum amount of resistance. Furthermore, the diverging legs provide a mechanically strong connection between the air terminals and the cable, since they act as braces to prevent swaying of the air terminals, and the tubular formation of the upright stem and diverging legs of the connector when it is finally assembled give the various parts thereof an inherent strength which will enable them to resist heavy strains. The diverging legs 1^b are shown as having a curvature, although the degree of curvature is not thought to be material, and the legs may be made straight if such is preferred.

In Figure 1 the invention is shown as applied to a building B. The conductor cable 3, which may be of any suitable construction, extends along the ridge of the building, and has one end thereof grounded at G, and the other end at H. A series of connectors are shown as applied thereto at intervals, said connectors being indicated at C, and the collector elements or air terminals being indicated by the numeral 8. It will be obvious that the connectors can be readily applied to the cable at any desired point and as many

of the air terminals or collector elements used as may be thought necessary for the protection of the building.

While one particular embodiment of the invention has been shown and described in detail for illustrative purposes, it will be understood that many modifications and changes can be made in the details of construction without departing from the spirit of the invention.

Referring to Fig. 7, one of the feet 2 of each of the connector sections 1 may have a prong 9 stamped therefrom, and when the two sections 1, 1 are assembled each of the cable receiving sleeves will be provided with a sharp prong 9 which will penetrate the cable and assist in fastening the connector thereto.

Having thus described my invention what I claim as new and desire to secure by Letters Patent is,

1. In lightning rod apparatus of the class described, the combination with a conductor and a collector, of a connector device comprising complementary substantially Y-shaped tubular sections having tubular conductor and collector engaging ends.

2. As a new article of manufacture, a connector device for lightning rod structures comprising a pair of corresponding sheet metal complementary tubular sections composed of a stem engageable by the collector and spaced tubular legs extending from said stem and terminating in conductor embracing clamping feet.

3. In lightning rod apparatus of the class described, the combination with a conductor and a collector having a sleeve at its lower end, of a connector device comprising complementary tubular sections forming at one end a stem receiving the collector sleeve and diverging legs extending from said stem and terminating in tubular conductor embracing feet, said sections having connecting means for holding them in tubular formation.

4. As a new article of manufacture, a connector device for lightning rod structures comprising a pair of corresponding sheet metal complementary tubular sections composed of a stem engageable by a collector and spaced tubular legs having tubular conductor embracing terminals, and hinging connections for the sections permitting the sections to be readily opened and closed with relation to each other.

5. As a new article of manufacture, a connector device for lightning rod structures comprising a pair of corresponding sheet metal complementary tubular sections composed of a stem engageable by the collector and spaced tubular legs having tubular conductor embracing terminals, hinging connections for the sections permitting the sections to be readily opened and closed with

relation to each other, and fastening elements carried by the respective sections and engageable about the same when arranged in close relation to hold the device in its tubular formation.

6. As a new article of manufacture, a connector device for lightning rod structures comprising complementary substantially Y-shaped tubular sections providing a collector

receiving stem at one end and conductor receiving feet at its other end, said device having a conductor penetrating element forming a part of one of the feet for positively engaging the conductor when in operative position thereon.
